UNITED STATES PATENT OFFICE.

COLLINGWOOD POLLARD, OF BRADFORD, ENGLAND.

DESIGN FOR A KINDLING-BLOCK.

SPECIFICATION forming part of Design No. 35,685, dated February 4, 1902.

Application filed December 18, 1901. Serial No. 86,420. Term of patent 14 years.

To all whom it may concern:

Be it known that I, COLLINGWOOD POLLARD, a subject of the King of Great Britain, residing at Bradford, England, have invented and produced a new and original Design for a Kindling-Block, of which the following is a specification, reference being had to the accompanying drawings, forming part thereof.

In the drawings, Figure 1 is a view of one side of the block, while Fig. 2 is a view of the opposite side. Fig. 3 is a view looking at the inside edge of Fig. 2, while Fig. 4 is an end view of Fig. 2.

The leading feature of the design is the general configuration or outline of the block, as shown in the drawings.

As will be seen, the block is made of one

piece, with diagonally-arranged ribs on one face and straight ribs on the other. The side walls of the block are parallel, while the ends of the block are cut incline, and it is the shape formed by this inclined cutting that gives the new configuration. The inclined ribs in Fig. 1 are shown at *a*, with the spaces between at *b*, while in Fig. 2 the ribs are shown at *c* and the spaces at *d*.

What I claim is—

The design for a kindling-block as herein shown and described.

COLLINGWOOD POLLARD.
